DISPLAY STAND

Harry A. Martin, Chicago, Ill.

Application August 5, 1936, Serial No. 94,436

4 Claims. (Cl. 34—26)

My invention relates to display stands, and more particularly to those which are heated or warmed in order to maintain their contents in proper condition, and my main object is to provide a novel heating means for portable nut stands usually seen on counters in stores, amusement places and other establishments catering to the public.

A further object of the invention is to provide a heating means which distributes the heat uniformly, in order that all the goods may be reached and kept fresh.

A still further object of the invention is to provide a heating unit which is conveniently housed within the stand and so concealed as to be invisible from the outside.

Another object of the invention is to provide a heating unit which is extremely compact and occupies a space heretofore wasted in stands of the portable type.

An additional object of the invention is to design the novel heating unit along lines of simplicity and economy.

With the above objects in view, and any others which may suggest themselves from the description to follow, a better understanding of the invention may be had by reference to the accompanying drawing in which—

Fig. 1 is a plan view of the improved display stand loaded with the goods;

Fig. 2 is an elevation of the same;

Fig. 3 is an enlarged elevation, partly broken away, of the display stand without the goods; and

Fig. 4 is a section on the line 4—4 of Fig. 3.

My invention deals particularly with that variety of display stands which are rotatable to enable the patron to pick the kind of nuts or other commodity carried in bags around the outside of the stand.

Stands of this kind are not fundamentally new, and according to the drawing are characterized by a base 10 from which rises a central post 11. On this post is centered for free rotation a skeleton frame 12 having the general formation of a polygonal prism whereby to present sections 12a to the outside. These sections are adapted to receive vertical cards 13 which carry series of Cellophane bags 14 in vertically-overlapping order. Each card carries a different variety of nut or other commodity, and the frame is turned by the patron to the kind wanted.

In the novel embodiment, the post 11 is not continuous, but is divided to permit the interposition of a looped support 15 formed from a sturdy, single piece of cast metal. The sections

of the post 11 screw into the upper and lower ends of the support and are secured by nuts 16 and 17. The lower section of the post rises through the support to receive an electrical socket 18 and lamp 19, it being understood that the said lower post section is tubular to permit the passage of a current supply cord 20 to the lamp.

The display frame 12 is centered with upper and lower bearings 12b and 12c on the sections of the post, these bearings being adjusted to permit the free rotation of the frame. The outer portion of the frame is deflected downwardly from the lower bearing by the use of inclined spider arms 12d, so that the post section will be concealed when the frame is loaded with the display cards.

In providing the lamp within the frame 12, it is my purpose to create and pass sufficient heat to the goods to counteract the deteriorating influence of atmospheric moisture thereon. Despite the use of sealed Cellophane bags for varieties of nuts, moisture penetrates them to render the nuts soggy and cause them to become rancid and stale-tasting in a short time, particularly in warm weather. This condition affects the lower sets of bags to a greater extent, since the upper bags are the ones that are first sold and pulled off. Therefore, my improvement deals not only with the heating or warming of the goods to the extent of becoming immune to moisture, but also to distribute the heat to all of the goods.

In carrying out the above idea, I apply a pair of sheet metal trays 21 and 22 to the upper and lower post sections respectively. The trays are marginally flanged at 21a and 22a, the flange 21a being downward, and the flange 22a being upward. Also, the tray 21 is of a larger diameter than the tray 22.

A cylindrical tube 23 of oiled paper board is fitted up into the tray 21 and depends downwardly therefrom; and a smaller tube 24 of the same character is disposed within the tube 23 and fitted to rest in the tray 22. The tubes 23 and 24 overlap to a limited degree. While the tube 24 maintains its position by its weight, the tube 23 is secured in any suitable manner to the tray 21. As an illustration, the securing clip 25 shown may be employed. This clip is a wire extending over the tray and formed with terminal hook bends 25a which seat in eyelet-reinforced perforations 25b made in the sides of the tube 23. The wire 25 is medially crossed and looped at 25c to give it some tension when engaged as in Fig. 3. Of course, when the tube 23 is to be dropped, such as for the renewal of the lamp

19, it is an easy matter to withdraw the hooks
25a and so release the tube.

It will be appreciated that with a lamp of
5 economical current capacity—40 watts or less—it
is possible to create and pass sufficient heat
through the cards and commodity-containing
bags to maintain the goods in proper condition.
As heat tends to rise, the upper bags would re-
ceive more heat than the lower ones, which would
10 be inconsistent with the requirements mentioned
before. I have therefore provided the spaced
and overlapping tube 23 in the nature of a hood
to create a downward passage for the escape of
heat, so that the lower bags not only receive the
15 heat generated in the tube 24 but also the warm
air escaping from the tube 23. My experiments
with a stand constructed as described have thor-
oughly and consistently demonstrated the action
just mentioned by retaining the freshness and
20 quality of the lower goods for many days or as
long as it requires for them to be sold.

In conclusion it will be evident that the im-
provement described above is an important ad-
dition to display stands of the type under con-
sideration. While it performs its function to
25 keep the goods fresh, it is fully concealed from
view and does not detract from the appearance
or accessibility of the stand and its goods. In
fact, it forms an added attraction by creating a
30 downward glow from the light passing through
the oiled paper board, so that a soft light is
spread and diffused over the base 10. Further,
the heating unit occupies a space which was for-
merly wasted, putting the same to a beneficial
35 use. Further, the support 15 lends the stand
rigidity and resists tendencies to draw or knock
the post sections or display frame out of aline-
ment. Still, the improvement is of a nature to be
simply constructed, easily assembled and handled,
40 and economically operated.

While I have described the invention along the
specific lines shown, the same is susceptible of
various changes and refinements, and I desire to
include such changes and refinements as coming
45 within the scope and spirit of the appended
claims.

I claim:—

1. In a rotatable refreshment stand, an in-
ternal heating unit to maintain the goods carried
by the stand in proper condition, and means to
distribute the heat to both the upper and lower
5 portions of the goods, said means comprising a
vertical tube about the lower portion of the heat
unit and a larger tube about the upper portion
thereof and overlapping the first-mentioned tube.

2. In a rotatable refreshment stand, an in-
ternal heating unit to maintain the goods carried
by the stand in proper condition, and means to
distribute the heat to both the upper and lower
10 portions of the goods, said means comprising a
cup-like tube about the lower portion of the heat
unit, and an inverted cup-like tube about the up-
per portion thereof, the second mentioned tube
15 being concentrically enlarged about and over-
lapping the first mentioned tube.

3. In a rotatable refreshment stand, an in-
ternal heating unit to maintain the goods car-
ried by the stand in proper condition and means
to distribute the heat to both the upper and low-
er portions of the goods, a vertical post divided
20 into upper and lower portions and forming an
axis for the rotation of the stand, trays carried
by the respective post portions and having mar-
ginal flanges directed toward each other, the
upper tray being of a larger diameter than the
25 lower, and vertical tubes fitted in the flanges of
the respective trays and overlapping with their
inner ends.

4. In a rotatable refreshment stand, an in-
ternal heating unit to maintain the goods carried
by the stand in proper condition, and means to
distribute the heat to both the upper and lower
30 portions of the goods, a vertical post divided into
upper and lower portions and forming an axis
for the rotation of the stand, trays carried by the
respective post portions and having marginal
flanges directed toward each other, the upper tray
35 being of a larger diameter than the lower, and
vertical tubes fitted in the flanges of the respec-
tive trays and overlapping with their inner ends,
said tubes being of a translucent material.

HARRY A. MARTIN.
